ENGINE STARTING MECHANISM

Romeo M. Nardone, Westwood, N. J., assignor to
 Bendix Aviation Corporation, South Bend, Ind.,
 a corporation of Delaware

Application July 23, 1942, Serial No. 452,071

2 Claims. (Cl. 171—324)

This invention relates to engine starting mechanism of the inertia type.

Operation of mechanism of this character usually involves acceleration of the inertia element, or elements, prior to movement of the engine-engaging element of the starter to engine-engaging position. This accelerating process may be manual, or it may involve use of power derived from an electric motor. My Patent No. 2,068,462 shows an inertia starter having an inertia element in the form of a flywheel which may be accelerated manually or by use of an electric motor; the connections between the motor and flywheel involving a uni-directional clutch which overruns when the manual accelerating means is employed—the motor thus remaining at rest, wherefore its commutator and brushes do not act as a drag on the flywheel during the accelerating process.

While this elimination of brush drag is desirable under these conditions of manual acceleration, there are occasions when the addition of the mass of the motor armature, to that of the flywheel, would provide a desirable increase in the total inertia effect, which increase would be even more substantial if the brush drag were to be removed.

In my Patent No. 2,261,402 there is disclosed a brush lifting mechanism operative to remove the brushes from contact with the motor commutator whenever it is desired to employ the manual accelerating means for actuating the flywheel, with the motor armature rotating therewith, to add to the inertia effect.

The present invention is based upon the concept of removing brush drag, whenever desired, by a different method, namely, by slackening the tension of the springs of the brush assembly, so that the brushes ride freely on the commutator surface, rather than being mechanically lifted out of contact with the commutator, as in my prior Patent 2,261,402, above referred to; the ultimate result being the same, to wit, a free rotation of the armature, unrestricted by any appreciable brush pressure.

As is well known, brush springs are commonly employed to ensure sufficient firmness of contact, as between the brush ends, on the one hand, and the commutator surface on the other. These springs are preadjusted to the desired degree of tension, to produce the degree of tension pressure necessary for firm contact. Usually each spring must be adjusted separately. The present invention provides a novel method for simultaneously varying the spring pressure as to all brushes of

the motor assembly, and by means that are operable from an external point, just prior to commencement of flywheel acceleration, when manual flywheel acceleration is to be resorted to; said spring varying means being otherwise locked in the position corresponding to normal spring pressure on all brushes.

These and other objects of the invention will become apparent from inspection of the following specification when read with reference to the accompanying drawings wherein is illustrated the preferred embodiment of the invention. It is to be expressly understood, however, that the drawings are for the purpose of illustration only, and are not designed as a definition of the limits of the invention, reference being had to the appended claims for this purpose.

In the drawings:

Fig. 1 is a longitudinal sectional view of a starting mechanism having my invention incorporated therein;

Figs. 2 and 3 are end views of the unit shown in Fig. 1;

Fig. 4 is a sectional view along line 4—4 of Fig. 1;

Fig. 5 is a sectional view of the jaw-engaging solenoid; and

Figs. 6, 7 and 8 are end and side views of the brush pressure controlling means.

In the drawings there is shown a representation, mainly diagrammatic, of one type of engine starting mechanism to which the present invention is applicable. As shown therein the flywheel 5 is disposed in alignment with the electric motor 8 constituting one of the alternative accelerating means referred to above; hub 6 of the flywheel being keyed to armature shaft 7. Interposed between the engine-engaging clutch member 9 and the flywheel 5 are the usual gear train and capacity controlling pre-set clutch, the former being shown as having at one end a high speed pinion 11 rotatable with flywheel 5, and at the low speed end a set of planet pinions 12 to rotate the barrel 13 housing the pre-set clutch 14 in the usual manner, (as illustrated in detail in Lansing Patent No. 1,833,948) whereby rotation is imparted to the engine engaging clutch element 9. Movement of the clutch member 9 into engagement with corresponding clutch member 10 of the engine is under the control of axially movable rod 16 passing centrally and slidably through clutch barrel 13 and adapted to actuate clutch member 9 through yieldable means 15, as in the aforesaid Lansing patent. The rod 16 is normally restrained in the clutch-retracting position

55

shown, by suitable means such as coiled torsion spring 17 (Fig. 2) corresponding to the coiled torsion spring 106 of the aforesaid Lansing patent, and is movable into the clutch meshing position by manual means attachable to the end portion 18 of bell-crank 19 (Fig. 2) or by energization of a solenoid 20 whose plunger 21 (see Figs. 2 and 5) connects with rod 16 by way of the intervening bell-crank 19 and the rockshaft 24 (Fig. 2) about which the spring 17 is coiled; the said rockshaft having the usual lever 26 attached at its inner end for pivotal connection with rod 16.

Adjustable screw 37 (Figs. 2 and 5) transmits, to section 38 of bell-crank 19, the thrust of plunger 21, when solenoid 20 is energized. Spring 17 is the opposing (and plunger returning) force.

In case of motor failure (or if the battery charge is weak) the starter may be operated by accelerating the flywheel by hand through the hand-cranking shaft 33 connecting with hub 27 of the barrel 13, by way of gears 34, 35 (Fig. 1). Hub 27 also serves as a support for "sun" gear 39.

The brush pressure controlling mechanism is shown in Figs. 4, 6, 7 and 8 as including a ring 41 having support upon a circular inner surface of the end section 49 of the motor housing; said ring 41 being shiftable about said supporting member 49 to a limited extent as determined by the length of arcuate slot 58 (Fig. 3) on the end surface of housing member 49, which slot receives a pin 46 (Figs. 1, 7 and 8) secured at its inner end to the section 47 of the ring 41, and at its outer end having a head 51 (Fig. 1) for retention of a coiled spring 54 and a manually operable knob 53 whose base 55 is slidable on pin 46 and normally rests in a circular depression 45 of housing member 49, to lock the ring 41 against rotation until such time as the knob 53 is manually pulled out, preparatory to shifting of the ring 41 for relaxation of brush pressure. The relaxation of brush pressure follows upon shifting of the ring 41 by reason of the action of levers 43 whose end pins 44 are located in slots formed in plates 75 spaced evenly about the ring 41 at locations corresponding to the locations of the commutator engaging brushes 76. For each brush 76 there is a spring 77 wound spirally about, and anchored to, a post, 80; the said posts 80 being keyed to, and hence rotatable by the levers 43 as the latter are shifted by rotation of the ring 41; each lever

and post assembly being journaled in a bushing 47 (Fig. 7) of non-conducting material, and all of said bushings 47 being embedded in the supporting yoke 40 which carries the brush-holding boxes 79. The yoke 40 is in turn secured to the housing member 9 by suitable means 86 (Figs. 1 and 8).

It will be noted that each lever 43 has a range of movement over an arc of about sixty degrees, which means that each spirally wound spring 77 will be wound or unwound to a corresponding degree each time the levers are swung, through manipulation of knob 53. This alternate winding and unwinding produces alternate application and release of engaging pressure on the brushes 76, and in each case the condition is self-retained, due to the action of spring 54 (Fig. 1) in holding the base 55 of knob 53 in one or the other of the two depressions 45, said two depressions being located at opposite ends of arcuate slot 58 (Fig. 3).

What is claimed is:

1. In a motor having a commutator and a plurality of commutator-engaging brushes, a plurality of spirally coiled springs having their inner ends anchored at their respective axes, one for applying pressure to each brush, means for simultaneously uncoiling all of said springs to a predetermined degree, while the brushes remain in contact with the commutator, said uncoiling means comprising a corresponding plurality of levers, each adapted to swing about the axis of coiling of its corresponding spring, and a single means for simultaneously swinging all of said levers, said single means including a locking mechanism for retaining the levers in the positions to which they have been swung.

2. In a motor having a commutator and a plurality of commutator-engaging brushes, a plurality of spirally coiled springs having their inner ends anchored at their respective axes, one for applying pressure to each brush, means for simultaneously uncoiling all of said springs to a predetermined degree, while the brushes remain in contact with the commutator, said uncoiling means comprising a corresponding plurality of levers, each adapted to swing about the axis of coiling of its corresponding spring, and a single means for simultaneously swinging all of said levers.
